UNITED STATES PATENT OFFICE

108,928

DESIGN FOR A RAIN STOCKING

Harry C. A. Behr, York, Pa., assignor of one-half
to Carroll H. Sweitzer, New Freedom, Pa.

Application February 5, 1938, Serial No. 74,918

Term of patent 14 years

To all whom it may concern:

Be it known that I, Harry C. A. Behr, a citizen of the United States, residing at York, in the county of York and State of Pennsylvania, have invented a new, original, and ornamental Design for a Rain Stocking, of which the following is a specification, reference being had therein to the accompanying drawing, forming part thereof, in which

Figure 1 is a view in side elevation, of a rain stocking, showing my new design.

Figure 2 is a view in front elevation.

I claim:

The ornamental design for a rain stocking, as shown.

HARRY C. A. BEHR.
